UNITED STATES PATENT OFFICE.

THOMAS E. WALKER, OF DETROIT, MICHIGAN, ASSIGNOR TO CRITALL CASEMENT WINDOW COMPANY, OF DETROIT, MICHIGAN, A CORPORATION OF MICHIGAN.

WEATHER STRIP FOR WINDOWS.

Application filed December 3, 1924. Serial No. 753,536.

To all whom it may concern:

Be it known that I, THOMAS E. WALKER, a citizen of the United States, residing at Detroit, in the county of Wayne and State 5 of Michigan, have invented certain new and useful Improvements in Weather Strips for Windows, of which the following is a specification, reference being had therein to the accompanying drawings.

10 This invention relates to weather strips for windows, and more particularly window frames and sashes made of metal, although the weather strips are applicable to frames and sashes made of wood.

15 My invention aims to provide weather strips that may be easily and quickly mounted in a window frame to insure a perfect fitting of sashes in the frame, so that there will not be any cracks, spaces and loose 20 connections permitting air and the elements to pass through the frame and interfere with the frame and its sashes as a closure. The weather strips are arranged in the frame to form channel guides for the sashes and 25 novel means is employed for establishing an intimate relation between the sashes and the frame, without interfering with an easy adjustment of the window sashes. Weather strips may also be used on the sill and lintel 30 of the window frame to ensure proper connection of the sashes with the frame when the sashes are closed.

35 It is a well known fact that metal sashes cannot be at all times maintained weather tight in a metal frame, particularly if such frame and sashes are of a comparatively low grade. It is in connection with such frames and sashes that my weather strips may be readily installed to compensate for 40 any poor fitting, and provision is made for producing a constant pressure on some of said strips so that the other strips are brought into cooperative relation with the pressure strips to ensure a thorough backing of the sashes within the window frame.

45 My invention further aims to provide a simple, durable and inexpensive window construction that will be hereinafter specifically described and then claimed.

50 Reference will now be had to the drawings, wherein

Figure 1 is a front elevation of a window frame embodying features of my invention;

Fig. 2 is an enlarged vertical cross sec-

tional view of the same with intermediate 55 parts of the frame broken away;

Fig. 3 is an enlarged horizontal sectional view of a portion of the window frame, and

Fig. 4 is an enlarged elevation of the inner wall of a stile with a mid rail partly in 60 section.

Reference will first be had to one of the stiles of a window frame, which is best shown in Fig. 3 as being composed of two Z bars 1 and 2 having flanges 3 and mid rail flanges 4. The flanges 3 are adapted to form the inner and outer side walls of the window frame and attached to said flanges by rivets 5 or other fastening means are angle bars 6 which extend between the flanges 4 and are provided with webs 7 abutting the bars 1 and 2 to assist in retaining said bars in position with the flanges 4 and the edges 8 of the angle bars 6 forming a mid rail on the stile. The angle bars 6 are preferably made of material lighter in weight than the Z bars 1 and 2 and said angle bars are adapted to cooperate with the bars 1 and 2 in forming wells 9 for weights or other devices that may be utilized 65 to facilitate adjustment of sashes in the window frame.

Suitably attached to the Z bars 1 and 2, in parallel with the mid rail, are retaining strips 10 which cooperate with the mid rail 85 in providing parallel sash ways 11. In each sash way 11 is a set of weather strips which are shiftable in a lateral direction with the weather strips of each set cooperating in forming a channel guide 12 for the 90 side rail 13 of the sash 14.

The outer weather strips are designated 15 and the inner strips are designated 16, the former being angular in cross section, and the latter substantially Z shaped. The strips of each set are arranged in overlapping relation on each Z bar 1 or 2 and are slotted, as at 17 so that screws 18 or the like may be attached to the Z bars 1 and 2 for 95 slidably holding the weather strips for lateral movement relative to each other. The inner weather strips 16 overlap each other on the mid rail 4 and said mid rail, at suitable intervals, has openings 19 for coiled expansion springs 20, said springs having the end convolutions thereof bearing against the inner weather strips 16 so as to force said weather strips outwardly 100 105

against the rails 13 of the sashes and cause said rails to crowd the outer weather strips 15 against the retaining rails 10. In consequence of this arrangement the inner and 5 outer weather strips will cooperate in packing the sashes relative to the frame stile and since the inner weather strips 16 overlap on the mid rail there will be a comparatively air tight connection between the 10 sashes and the window frame.

The mid rail at suitable intervals is provided with rivets 21 or other fastening means for holding the bars 1, 2 and 6 in an assembled relation, and it is obvious 15 that in lieu of rivets spot welding may be resorted to for providing a rigid structure.

The weather strips cooperate in forming channel guides in which the window sashes may readily slide and this is particularly 20 true when the weather strips are made of parts or a material which will not corrode when exposed to the elements.

Practically the same manner of packing the side rails of the sashes 14 may be utilized in packing a sash top rail 22 relative to a lintel 23, and the sash bottom rail 24 relative to a sill 25. The lintel and sill are of suitable structural shapes and are preferably formed with pressed out hollow beads 30 or strips 30 apertured at intervals for transversely arranged coiled expansion springs 26 which have the end convolutions thereof bearing against angle weather strips 27 placed in overlapped relation on each bead 35 or strip 30 and retained thereon by screws 29 or the like. The weather strips 27 are slidable laterally on the beads or strips 30 and are preferably provided with inclined side walls for snugly engaging in the channel 40 top and bottom rails of the sashes, as best shown in Fig. 2. The weather strips 27 will be distended against the rails of the sashes and afford a sealed connection when the sashes are closed, and when either sash is 45 open the weather strips cannot become displaced because of the screws 29, and it is obvious that the springs 26 will be housed during an open condition of the sash.

It is believed that the utility of my weather strips will be apparent without further description, and while in the drawings there is illustrated a preferred embodiment of my invention, it is to be understood that the structural elements are susceptible to such 55 variations and modifications as fall within the scope of the appended claims.

What I claim is:-

1. In a window frame having a sashway, a sash slidable in the frame sashway, 60 said sash having channel rails, weather strips in the frame sashway forming guides for said sash, and weather strip holding means carried by said frame and extending into said channel rails.

65 2. In a window frame having a sashway,

a sash slidable in the frame sashway and opposed weather strips slidably connected to the window frame, said opposed weather strips forming guides for said sash.

3. In a window frame having a sashway, 70 a sash slidable in the frame sashway, and weather strips in overlapped relation in the frame sashway and supported therein for lateral movement and to form guides for said sash.

4. In a window frame, a rail, a retaining strip, a sash slidable between said rail and strip, a non-resilient bodily shiftable weather strip between said rail and sash, a non-resilient bodily shiftable weather strip between said sash and retaining strip, and means located in said rail, operable against one weather strip to cause said sash to shift the other weather strip. 80

5. In a window frame, a rail, a retaining strip, a sash slidable between said rail and strip, a weather strip between said rail and sash, a weather strip between said sash and retaining strip, said weather strips being in overlapped relation and supported for lateral movement by said frame, and means operable against one weather strip to cause said sash to shift the other weather strip. 90

6. In a window frame, a rail, a retaining strip, a sash slidable between said rail and strip, a weather strip between said rail and sash, a weather strip between said sash and retaining strip, said weather strips being in overlapped relation with one of said weather strips forming two walls of a channel guide 100 for said sash, and the other weather strip a third wall of the channel guide, and means operable against one weather strip to cause said sash to shift the other weather strip. 105

7. In a window frame, a mid rail, retaining strips, sets of weather strips between said mid rail and said retaining strips providing channel guides, sashes slidable in the channel guides, and means in said mid rail bearing against a weather strip of each set to cause said weather strips to pack said sashes relative to said mid rail and said retaining strips. 110

8. A window frame as called for in claim 7, wherein weather strips of each set overlap on said mid-rail. 115

9. In a window frame; a mid-rail; retaining strips; sashes slidable in said frame; outer weather strips between said sashes and said retaining strips; inner weather strips between said sashes and said mid-rail; and means in said mid-rail forcing said inner weather strips against said sashes, said sashes against said outer weather strips, and said outer weather strips against said retaining strips. 120

10. A window frame as called for in claim 9 wherein said inner weather strips overlap on said mid-rail. 125

11. A window frame as called for in claim 9, wherein said inner weather strips overlap said outer weather strips and are slidably supported by said frame.
- 5 12. In a window frame, a slidable sash, overlapped weather strips engaging walls of said sash, and means bringing pressure to bear on said weather strips to cause said strips to frictionally engage said sash.
- 10 13. A window frame as called for in claim 12, wherein each strip is angular in cross section with edges of said strips slidably supported from said frame.
14. In a window frame, a channel shape
- 15 guide for a sash, said guide being formed of opposed weather strips, each angular in cross section and slidable relative to each other.
15. In a window frame, a channel shape
- guide for a sash, said guide being formed of opposed non-resilient bodily shiftable weather strips, and means engaging one weather strip to cause it, through the medium of the sash, to shift the other weather strip. 20
16. In a window frame, a sash, and non-resilient bodily shiftable weather strips connected together for lateral movement relative to said frame and having walls engaging inner and outer walls of said sash to 25 seal said sash relative to said frame.

In testimony whereof I affix my signature in the presence of two witnesses.

THOMAS E. WALKER.
